Patented Dec. 23, 1919.

James Warren Samuel INVENTOR

BY

N. J. Bissell ATTORNEY

UNITED STATES PATENT OFFICE.

JAMES WARREN SAMUEL, OF CEDARHURST, NEW YORK.

DESIGN FOR A COMBINED ASH-TRAY AND FLAGPOLE.

54,334.

Specification for Design.

Patented Dec. 23, 1919.

Application filed June 16, 1917. Serial No. 175,218. Term of patent 3½ years.

To all whom it may concern:

Be it known that I, JAMES WARREN SAMUEL, a citizen of the United States, residing at Cedarhurst, Long Island, in the county of Nassau and State of New York, have invented a new, original, and ornamental Design for a Combined Ash-Tray and Flagpole, of which the following is a specification, reference being had to the accompanying drawing, forming part thereof.

In the drawing:

The figure is a perspective view of the combined ash tray and flagpole showing my new design.

I claim:

The ornamental design for a combined ash tray and flagpole, as shown.

JAMES WARREN SAMUEL.
